UNITED STATES PATENT OFFICE.

ROBERT T. WOOD, OF BUFFALO, TEXAS.

DESIGN FOR A POST-BASE.

SPECIFICATION forming part of Design No. 33,783, dated December 25, 1900.

Application filed November 30, 1900. Serial No. 38,271. Term of patent 7 years.

To all whom it may concern:

Be it known that I, ROBERT T. WOOD, a citizen of the United States, residing at Buffalo, in the county of Leon and State of Texas, 5 have produced a new and original Design for a Post-Base, of which the following is a specification.

This invention relates to a design for a post-base, and the essential feature resides in the 10 design as illustrated in the accompanying drawings, wherein—

Figure 1 is a perspective view of a post-base embodying the features of the design. Fig. 2 is a transverse vertical section of the same. 15 The numeral 1 designates an upper member in the form of an inverted frustum of a quadrangular pyramid having upper curved bevel edges 2, surrounding a square socket-

opening 3. The lower portion 4 of the device is in the form of an inverted quadrangular pyramid having sides at a different angle from those of the upper member 1, the said lower portion having a wedge-like appearance.

Having thus described the invention, what is claimed as new is—

The design for a post-base, herein shown and described. 25

In testimony that I claim the foregoing as my own I have hereto affixed my signature in the presence of two witnesses.

R. T. ^{his} X WOOD.
